UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,264,153.

Specification of Letters Patent. Patented Apr. 30, 1918.

Application filed July 2, 1917. Serial No. 173,170.

To all whom it may concern:

Be it known that I, HENRY P. CLAUSEN, a citizen of the United States, and residing at Mount Vernon, in the county of West-
5 chester and State of New York, have invented certain new and useful Improvements in Telephone Systems, of which the following is a full, clear, concise, and exact description.

10 This invention relates to telephone systems, and particularly to arrangements within private branch exchange systems where machine switching apparatus is used.

The object of the invention is to provide
15 means whereby a number of normally independent lines may be instantly linked together, and the subscribers of such lines summoned to a conference over the telephone.

20 According to one feature of the invention, certain lines are connected to a special set of connector terminals in multiple, through apparatus individual to each, so that, although normally independent, they may be
25 instantly connected together. According to another feature of the invention, each of these lines, which is busy at the time that it is seized through this special set of terminals, has a distinctive tone placed thereon
30 for the purpose of warning parties who are conversing that a special call is being made, and that they should thereupon release the lines for such conference service.

It is thought that the invention will best
35 be understood by reference to the accompanying drawing, in which two normally independent lines with their connections are diagrammatically shown.

40 A substation S^1 and a substation S^2 are shown, both having identical circuits. The substation S^1 may be reached through the terminals t^1 , t^2 and t^3 in any suitable type of automatic switch. The substation S^2 may be reached through terminals t^4 , t^5 and
45 t^6 in a similar manner. The brushes b^1 , b^2 and b^3 represent the brushes of the connector switch which is adapted to travel over and make contact with the various terminals mentioned. The subscriber at station S^1 , upon removing his receiver from
50 the switchhook, establishes a circuit from ground, the left-hand winding of line relay LR^1 , the normal contact and inner right-hand armature of relay T^1 , the inner right-hand armature and contact of cutoff relay
55

CO^1 , to and through the apparatus of the substation S^1 , the contact and outer right-hand armature of cutoff relay CO^1 , the outer right-hand armature and normal contact of relay T^1 , the right-hand winding of relay LR^1 , to battery and ground. Relay LR^1 is energized in this circuit and serves in any well known manner to actuate a line finder switch, which will extend the calling line to an idle selector or connector switch, and, through the manipulation of the dial D^1 , a connection may be thereupon established. Similar action may be had in the case of substation S^2 through the energization of relay LR^2 .

A connection extended to the brushes b^1 , b^2 and b^3 of the connector switch, and placed on terminals t^1 , t^2 and t^3 , for instance, will seize the line of substation S^1 , and, through a battery connection to the brush b^3 , will energize the cutoff relay CO^1 . The establishment of such a connection is well known to those skilled in the art, and need not further be described, except to state that the cutoff relay CO^1 has an additional armature by means of which a distinctive tone is placed on the subscriber's line, as will be hereinafter described.

Assume now that a subscriber in authority over those at substations S^1 and S^2 wishes to call those parties for conference purposes. Through proper manipulation of his calling device, he will direct the brushes b^1 , b^2 and b^3 to the terminals t^7 , t^8 and t^9 . Assuming the substation S^1 to be busy and the substation S^2 to be idle, then a circuit is established from the battery connection to brush b^3 , the terminal t^9 , through the winding of relay T^1 to ground, whereupon the relay T^1 will actuate its armatures and establish a circuit from ground, battery, the secondary winding of induction coil I^1 , the left-hand armature and contact of relay T^1 , the left-hand armature and alternate contact of relay CO^1 to the upper side of the line leading to substation S^1 . The primary of the induction coil I^1 is connected to a source of alternating current of such character that a distinctive tone is produced thereby, and the subscriber at S^1 , hearing in his receiver this tone, recognizes the fact that his superior officer is making a special conference call, and thereupon releases his connection. The cutoff relay CO^1 thereupon retracts its armatures and the following op-

- erations are carried out, which are similar to the operations of the apparatus associated with the substation S^2 after the relay T^2 has been energized.
- 5 A circuit is established from a source of ringing current through the relay TR^1 , the normal contact and inner right-hand armature of relay LR^3 , alternate contact and inner right-hand armature of relay T^1 , the inner right-hand armature and contact of relay CO^1 to and through the signaling apparatus of the substation S^1 , the contact and outer right-hand armature of relay CO^1 , the outer right-hand armature and alternate contact of relay T^1 , the outer right-hand armature and normal contact of relay LR^3 , to ground. The current traveling through this path is not sufficient to cause the actuation of the tripping relay TR^1 until the subscriber S^1 removes his receiver from its hook. When this occurs, relay TR^1 becomes energized, attracts its armatures, and sets up a circuit from ground, the armature and contact of relay TR^1 , the right-hand winding of relay LR^3 to battery and ground. Relay LR^3 thereupon attracts its armatures and a circuit is established from ground, the left-hand winding of relay LR^3 , the alternate contact and inner right-hand armature of relay LR^3 , the alternate contact and inner right-hand armature of relay T^1 , the inner right-hand armature and contact of relay CO^1 , to and through the apparatus at the substation S^1 , the contact and outer right-hand armature of relay CO^1 , the outer right-hand armature and alternate contact of relay T^1 , the outer right-hand armature and alternate contact of relay LR^3 , the right-hand winding of relay LR^3 to battery and ground. In this manner, relay LR^3 is placed under control of the line terminating in substation S^1 , and such substation is supplied with talking current through the windings thereof.
- 45 At the same time, battery potential is placed on the third conductor of the line from ground, battery, the secondary winding of induction coil I^1 , the left-hand armature and contact of relay T^1 , the left-hand armature and normal contact of relay CO^1 , to the third or test conductor of this line. It should be noted here that this battery potential is insufficient to cause the energization of relay CO^1 , but is sufficient to prevent the seizure of this line by a connector switch through the terminals t^1 , t^2 and t^3 .
- Condensers C^1 , C^2 , C^3 and C^4 are placed between the connector switch represented by the brushes b^1 , b^2 and b^3 and the lines of

substations S^1 and S^2 , whereby the subscribers at S^1 and S^2 only have control of the relays LR^3 and LR^4 respectively.

Upon the completion of the conference, and the replacing of the receivers on their hooks at the respective substations, the relays LR^3 and LR^4 are released, and, upon the removal of the brushes b^1 , b^2 and b^3 from the terminals t^1 , t^2 and t^3 , the lines are again placed in their normal conditions.

What is claimed is:

1. In a telephone system, a connector switch, a plurality of normally independent lines terminating therein, means including said switch for extending a connection to each of said lines separately, and means also including said switch for automatically extending a connection to all of said lines as a group.

2. In a telephone system, a connector switch, a plurality of normally independent lines terminating therein, means including said switch for extending a connection to each of said lines separately, and means also including said switch for simultaneously and automatically extending a connection to all of said lines as a group.

3. In a telephone system, a connector switch, a plurality of normally independent lines, means for preventing the extension of a connection to a busy one of said lines, and means including said switch for extending a connection to said plurality of lines as a group.

4. In a telephone system, a plurality of normally independent lines, automatic switches for interconnecting said lines, means for preventing the extension of a connection to a busy one of said lines, means including said automatic switches for extending a connection to said plurality of lines as a group, and means for signaling a busy one of said lines.

5. In a telephone system, a plurality of normally independent lines, automatic switches for interconnecting said lines, means including said automatic switches for extending connections to said lines separately, means including said automatic switches for extending connections to said lines as a group, means for preventing the extension of a connection to a busy one of said lines, and means responsive to the means for establishing a group connection for signaling a busy one of said lines.

In witness whereof, I hereunto subscribe my name this 29th day of June A. D., 1917.

HENRY P. CLAUSEN.
